[57] CLAIM

The ornamental design for a ski with transparent upper foreportion, as shown and described.

DESCRIPTION

FIG. 1 is a top plan view of a ski with transparent upper foreportion showing my new design;

FIG. 2 is a right side elevational view thereof;

FIG. 3 is a left-side elevational view of an alternate embodiment thereof;

FIG. 4 is a bottom plan view of the ski of FIG. 1;

FIG. 5 is a rear elevational view thereof;

FIG. 6 is a front elevational view thereof; and,

FIG. 7 is a perspective view of the design shown in FIGS. 1, 2, 4-6.

FIG. 1

FIG. 2

FIG. 3

FIG. 4

FIG. 5

FIG. 6

FIG. 7
